US00D705799S

(12) **United States Design Patent**
Funabashi et al.

(10) **Patent No.:** **US D705,799 S**
(45) **Date of Patent:** ** *May 27, 2014

(54) **DISPLAY PANEL OR SCREEN WITH
GRAPHICAL USER INTERFACE**

(75) Inventors: **Yoshimitsu Funabashi**, Tokyo (JP);
Shunsuke Kunieda, Tokyo (JP)

(73) Assignee: **Sony Computer Entertainment Inc.**,
Tokyo (JP)

(*) Notice: This patent is subject to a terminal disclaimer.

(**) Term: **14 Years**

(21) Appl. No.: **29/371,767**

(22) Filed: **Sep. 8, 2011**

(30) **Foreign Application Priority Data**

Jul. 11, 2011 (JP) D2011-015887

(51) **LOC (10) Cl.** **14-04**

(52) **U.S. Cl.**

USPC **D14/487**

(58) **Field of Classification Search**

USPC D14/485-489, 492; D21/333; 715/840

See application file for complete search history.

(57) **CLAIM**

The ornamental design for a display panel or screen with graphical user interface, as shown and described.

DESCRIPTION

FIGURE is a front elevational view of a display panel or screen with graphical user interface showing our new design. The broken lines showing of a display panel or screen and other elements form no part of the claimed design.

1 Claim, 1 Drawing Sheet
